[57] CLAIM

The ornamental design for a headworn imaging unit with visor, substantially as shown and described.

DESCRIPTION

FIG. 1 is a perspective view of a headworn imaging unit with visor showing my new design, the broken lines indicate environmental structure and form no part of the claimed design;

FIG. 2 is a right side elevational view thereof;

FIG. 3 is a top plan view thereof;

FIG. 4 is a front elevational view thereof;

FIG. 5 is a rear elevational view thereof;

FIG. 6 is a left side elevational view thereof; and,

FIG. 7 is a bottom plan view thereof.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 300,476
